UNITED STATES PATENT OFFICE

119,585

DESIGN FOR A TOY ROTARY UNIT

Frederick K. Formis, Chattanooga, Tenn.

Application January 4, 1940, Serial No. 89,298

Term of patent 7 years

To all whom it may concern:

Be it known that I, Frederick K. Formis, a citizen of the United States, residing at Chattanooga, in the county of Hamilton and State of Tennessee, have invented a new, original, and ornamental Design for Toy Rotary Units, of which the following is a specification, reference being had to the accompanying drawing, forming part thereof.

Figure 1 is a view of the obverse face of a toy rotary unit, showing my new design.

Figure 2 is a side view of the same.

Figure 3 is a view of the reverse face of said toy rotary unit.

I claim:

The ornamental design for a top rotary unit, as shown.

FREDERICK K. FORMIS.
